(57) **CLAIM**

The ornamental design for a movable mounting arm, as shown and described.

DESCRIPTION

FIG. 1 is a bottom perspective view of a movable mounting arm showing our new design. The movable mounting arm is shown with a monitor (in broken lines) in an open position; FIG. 2 is a front view thereof; FIG. 3 is a rear view thereof; and FIG. 4 is a left side view thereof; FIG. 5 is a right side view thereof; FIG. 6 is a top plan view thereof; FIG. 7 is a bottom plan view thereof; and, FIG. 8 is another bottom perspective view thereof, with the monitor in a closed position. The broken lines shown in the drawings are included for the purpose of illustrating elements of the mounting arm and form no part of the claimed design.
